UNITED STATES PATENT OFFICE.

SIMON S. NEWMAN, OF NEW YORK, N. Y.

DESIGN FOR A SANITARY POWDER-RECEPTACLE.

47,605.

Specification for Design.

Patented July 20, 1915.

Application filed May 7, 1915. Serial No. 26,663. Term of patent 3½ years.

To all whom it may concern:

Be it known that I, SIMON S. NEWMAN, a citizen of the United States, residing at New York-city, in the county and State of New York, have invented a new and ornamental Design for Sanitary Powder-Receptacles, of which the following is a specification, reference being had to the accompanying drawing, forming part thereof.

The figure is a perspective view of a sani-

tary powder receptacle, showing my new design.

I claim:—

The ornamental design for a sanitary powder receptacle, as shown.

SIMON S. NEWMAN.
